UNITED STATES PATENT OFFICE

2,604,161

WINDOW SHUTTER

Frederick William Bopp and Edward Otto Bopp,
Kansas City, Mo.

Application December 6, 1948, Serial No. 63,765

3 Claims. (Cl. 160—176)

1

This invention relates to improvements in window shutters or blinds, and is an improvement over the shutters shown in our co-pending applications, Serial No. 577,359½ filed February 12, 1945, which issued August 29, 1950 as Patent No. 2,520,272; Serial No. 741,150, filed April 14, 1947, which issued August 29, 1950 as Patent No. 2,520,273; Serial No. 18,186, filed March 31, 1948, which issued October 3, 1950 as Patent No. 2,524,372; and Serial No. 54,219, filed October 13, 1948.

The principal object of the present invention is the provision, in a window shutter having a plurality of parallel, vertically disposed flexible slats, of improved and simplified means whereby said slats may be rotated about their respective longitudinal axes to control the passage of light and air therebetween.

Another object of the present invention is the provision of a window shutter comprising support members carried adjacent the upper and lower edges of a window, like series of vertically disposed shafts carried by each of said support members, vertically disposed flexible slats each connected at its opposite ends to corresponding shafts of said series of shafts, a pinion carried by each of said shafts, and a rack connecting said pinions associated with each series of shafts whereby said slats may be oscillated each about its longitudinal axis, said racks being retained in operative position by its disposition between said pinions and the associated support member.

A further object is the provision, in a shutter of the character described, of means whereby any one of said pinions may be selectively disengaged from its driving rack, whereby the slat associated therewith may be adjusted individually.

Other objects are simplicity and economy of construction, ease of assembly, and adaptability for use wherever a shutter for controlling light and air is needed.

With these objects in view, as well as other objects which will appear in the course of the specification, reference will be had to the drawing, wherein:

Figure 1 is a front elevational view of a window shutter embodying the present invention, mounted on the inside of a window frame.

Fig. 2 is a sectional view taken on line II—II of Fig. 1.

Fig. 3 is a sectional view taken on line III—III of Fig. 1.

Fig. 4 is an enlarged and foreshortened sectional view taken on line IV—IV of Fig. 1.

2

Fig. 5 is an enlarged and foreshortened plan view of the shutter.

Fig. 6 is an enlarged fragmentary section taken on line VI—VI of Fig. 5, with parts broken away.

Fig. 7 is an enlarged fragmentary section taken on line VII—VII of Fig. 5, with parts left in elevation and broken away.

Fig. 8 is a fragmentary section taken on line VIII—VIII of Fig. 6.

Fig. 9 is a fragmentary section taken on line IX—IX of Fig. 7.

Fig. 10 is an enlarged section taken on line X—X of Fig. 4.

Fig. 11 is an enlarged fragmentary section taken on line XI—XI of Fig. 5.

Fig. 12 is a view similar to Fig. 6, showing a modified form of rack construction.

Fig. 13 is a plan view of the parts shown in Fig. 12.

Fig. 14 is a fragmentary sectional view taken on line XIV—XIV of Fig. 13.

Like reference numerals apply to similar parts throughout the several views, and the numeral 2 applies to a window frame of the usual type.

25 A pair of mounting brackets 4 are mounted respectively at opposite sides of said window frame on the inner face thereof adjacent the upper and lower ends of the window. Each of said brackets comprises a vertically disposed sheet of metal projecting outwardly from said window frame and having a flange 6 at its rearward edge adapted to be secured to said window frame by screws 8. A front or cover panel 10 extends between the outer ends of said upper and lower

35 pairs of brackets, and are removably attached to said brackets by means of corner fixtures 12. Said corner fixtures each comprise a sheet of metal having a portion 14 disposed adjacent the outer surface of the associated mounting bracket, the upper and lower edge portions of portion 14 being rebent inwardly to form channels 16 adapted to slidably engage the upper and lower edge portions of bracket 4, and a portion 18 disposed adjacent the outer surface of front panel 10 and having its upper and lower edge portions rebent

40 inwardly to form channels 20 for engaging the upper and lower edge portions of front panel 10. Thus said front panels may be removed simply by slidably disengaging corner fixtures 12 from mounting brackets 4. An inwardly opening, horizontally disposed channel 22 is welded or otherwise securely fixed to the inner surface of each bracket 4.

45 Referring principally to the structure at the top edge of the window, as shown in Figs. 4 to 9,

55

it will be seen that a horizontally disposed support channel 24 extends between mounting brackets 4, the end portions thereof being slidably disposed in channels 22 and removably secured therein by bolts 26. Said channel opens upwardly, and comprises base portion 28 and side walls 30 and 32. A series of vertically disposed horizontally spaced apart shafts 34 are carried for rotational and longitudinal movement by base portion 28 of channel 24. All of said shafts are identical, and may be economically stamped from sheet metal or the like. As best shown in Fig. 6, each shaft comprises an axial portion 36, and a transversely disposed horizontal hook portion 38 positioned beneath channel 24 to engage the slats as hereinafter described. Axial portion 36 of each shaft is rectangular in cross section, and passes rotatably through a round hole 40 formed therefor in channel base portion 28. Axial portion 36 of the shaft is reduced in width adjacent the lower surface of channel base 28, thereby forming shoulders 42 adapted to engage said channel base to limit the upward movement of the shaft.

A pinion 44 is carried slidably on the upwardly extended end portion of each shaft 34. All of said pinions except one is provided with a central rectangular hole 46 through which said shaft extends, thereby preventing rotation of said pinion on said shaft. One of said pinions, further designated by the numeral 48, and disposed at the right end of the shutter as viewed in Fig. 5, is provided with an enlarged, substantially square, central hole 50, as shown in Figs. 7 and 9. A polygonal tube 52 is disposed beneath support channel 24, being adjacent and parallel to the shaft 34 associated with pinion 48, and said tube is provided with an upwardly projecting non-circular extension 54 which, together with the associated shaft 34, projects upwardly through support channel base 28 and through square hole 50 of pinion 48, the shape of said hole being such as to prevent relative rotation of extension 54 and shaft 32, and to prevent rotation of pinion 48 thereon. A helical compression spring 56 is disposed about the upwardly extended end portion of each shaft 34, bearing at its lower end against pinion 44 and at its upper end against a pin 58 inserted transversely through said shaft adjacent its upper end. Spring 56 associated with pinion 48 also encircles tube extension 54, and pin 58 passes through said extension as shown in Fig. 7, thereby securing said tube member in position. Springs 56 serve to urge shafts 34 upwardly, and to retain pinions 44 against base 28 of channel 24 regardless of the longitudinal positioning of said shafts.

It will be noted, as in Fig. 4, that pinions 44 are disposed entirely within support channels 24, and that the outer ends of the teeth of said pinions pass in close proximity to side wall 30 of said channel. The toothed portion of each of said pinions is held in spaced relation above base portion 28 of channel 24 by hub 60, as shown in Fig. 6. As shown in Figs. 6, 8 and 9, a planar rack 62 lies slidably against the inner surface of side wall 30 of channel 24, and meshes with each of pinions 44 associated with said channel. Said rack comprises an elongated sheet of metal having a plurality of slots 64 formed therein for receiving the teeth of pinions 44. Since said slots are closed at both ends, the engagement of said pinion teeth therein serves to retain the rack securely in place within channel 24 without

screws, bolts, or other fasteners. This represents a substantial simplification and economical saving over structures wherein the rack must be attached to the supporting structure by independent means, wherein said fastening means must be of considerable accuracy in order to insure proper meshing of the rack and the pinions. In the present structure the only fasteners required for assembling shafts 34, springs 56, pinions 44 and rack 62 to channel 24 are pins 58 inserted through the end portions of said shafts.

As shown in Figs. 3 and 4, support channel 24 and the structure carried thereby at the bottom of the window is identical with that at the top of the window, except that it is inverted. A plurality of flexible vertical slats or strips 66 are disposed in parallel relation between the upper and lower series of shafts 34. Said strips may be made of fabric or other suitable flexible material, and each slat is looped at each end as at 68 to engage the transverse hook portion 38 of shafts 34 at the top and bottom of the window. Said slats are so positioned that their longitudinal edge portions overlap when the slats are moved to substantially coplanar relation, as shown in Fig. 1 and in solid lines in Fig. 2, thereby completely closing the window opening. The slats are of such length that springs 56 are slightly compressed, said springs thereby maintaining said slats taut. Said springs will also take up slight variations in the length of the slats caused by inaccuracies of manufacture.

Slats 66 may be turned about their respective longitudinal axes by means of a vertical rod 70 having its end portions carried slidably in tubes 52 at the top and bottom of the window. Said rod is polygonal in cross section, and said tubes are correspondingly shaped, as shown in Fig. 10, whereby rotation of said rod in said tubes is prevented. Said rod is supported by a collar 72 clamped thereon by set screw 74 and adapted to rest on the upper end of lower tube 52. Rod 70 may be manually oscillated by a handle 76 pivoted thereto at 78. Said handle may be pivoted to lie against said rod when not in use, as shown in solid lines in Fig. 1, or extended as shown in dotted lines whenever it is desired to adjust the shutter.

Thus when rod 70 is turned, pinions 48 associated therewith will be turned, and these pinions will drive racks 62 to turn the remainder of pinions 44 and shafts 34. Slats 66 carried by said shafts may thereby be continuously adjusted from a closed, substantially coplanar position, as shown in Figs. 1 and 2, to a full open position as shown in dotted lines in Fig. 2, wherein the slats are substantially normal to the plane of the window. The slats may be oscillated through substantially 180 degrees.

By lifting rod 70 free from the lower tube 52, the upper or lower ends of the slats may be turned independently of the opposite ends, thereby twisting said slats about their longitudinal axes. When the desired angle of twist is obtained, rod 70 may be reinserted in tube 52. While a hexagonal rod is shown, it is apparent that a rod having any regular polygonal shape could be used to provide the desired accuracy of adjustment. The slight shortening of the slats caused by said twisting is compensated by springs 56, which permit inward movement of shafts 34.

In the modified form shown in Figs. 12 to 14, a rack 80 is used in place of rack 62 of the preferred form. Said modified rack comprises a flange 82 which is disposed slidably against base portion

28 of channel 24, and a plurality of upwardly extending teeth 84 which are disposed against side wall 30 of channel 24. Flange 82 is disposed between the edge portions of pinions 44 and channel base 28, said pinions being provided with hubs 86 which elevate the toothed portions of said pinions above channel base 28 sufficiently to permit free sliding movement of flange 82. Teeth 84 engage the teeth of pinions 44. The structure of the modified form is otherwise the same as the preferred form. Thus, as in the preferred form, rack 80 is maintained in position in channel 24 by pinions 44. However, the modified form has the advantage that should it be desired to adjust a single slat to bring it into desired relation with the other slats, pinion 44 associated with that slat may be lifted against the pressure of spring 56 sufficiently to clear the teeth 84 of rack 80. Said pinion may then be turned as far as desired and allowed to return to engagement with rack 80. The modified form is also more easily assembled.

While a specific embodiment of our invention has been disclosed, it is apparent that many minor changes of construction and operation could be made without departing from the spirit of the invention.

What we claim is:

1. A support and operating structure for a window shutter or the like including a plurality of parallel slats, said support and operating structure comprising an upwardly opening elongated horizontal channel adapted to be secured to a window frame at the upper edge thereof, a series of geared pinions carried by said channel for rotation on vertical axes and disposed within said channel in a straight line, the teeth of said pinion extending in close proximity to one of the side walls of said channel, each of said pinions being adapted to be connected to one end of one of said slats, and an elongated rack disposed slidably against the inner surface of said channel side pinions, said pinions engaging said rack so as to retain said rack in said channel.

2. A support and operating structure for a window shutter or the like including a plurality of parallel slats, said support and operating structure comprising an upwardly opening elongated horizontal channel adapted to be secured to a window frame at the upper edge thereof, a series of geared pinions carried by said channel for rotation on vertical axis and disposed within said channel in a straight line, the teeth of said pinion

extending in close proximity to one of the side walls of said channel, each of said pinions being adapted to be connected to one end of one of said slats, and an elongated planar rack disposed slidably against the inner surface of said channel side wall and meshing with each of said pinions, said rack having a thickness greater than the spacing between said pinion teeth and said channel side wall and having a continuous series of transverse, closed-end slots formed therein for receiving said pinion teeth.

3. A support and operating structure for a window shutter or the like including a plurality of parallel slats, said support and operating structure comprising an upwardly opening elongated horizontal channel adapted to be secured to a window frame at the upper edge thereof, a series of geared pinions carried by said channel for rotation on vertical axes and disposed within said channel in a straight line, the teeth of said pinion extending in close proximity to one of the side walls of said channel, each of said pinions being adapted to be connected to one end of one of said slats, and having its peripherical edge portion disposed in spaced relation above the web of said channel, and an elongated rack disposed slidably against said channel side wall and meshing with each of said pinions, said rack being provided with a longitudinal flange extending between said channel web and the edge portions of said pinions, whereby said rack is retained in said channel.
